UNITED STATES PATENT OFFICE.

CASPER BICKEL, OF SHELBURNE FALLS, MASSACHUSETTS.

BICYCLE-PEDAL.

SPECIFICATION forming part of Letters Patent No. 669,676, dated March 12, 1901.

Application filed March 10, 1900. Serial No. 8,219. (No model.)

To all whom it may concern:

Be it known that I, CASPER BICKEL, a citizen of the United States, residing at Shelburne Falls, in the county of Franklin and State of Massachusetts, have invented certain new and useful Improvements in Bicycle-Pedals; and I do hereby declare the following to be a full, clear, and exact description of the invention, such as will enable others skilled in the art to 5 o which it appertains to make and use the same.

My invention relates to an improvement in 10 pedals for bicycles, the object being to provide a pedal of simplicity in construction, whose parts can be readily assembled or taken 15 apart, which will be secure against accidental disarrangement when in use, and whose bearings are rendered practically dust-proof.

The invention consists in the construction 20 hereinafter described, and embodied specifically in the claims.

Figure 1 is a plan view, partly in section, 25 of my pedal. Fig. 2 is a side view of the spindle. Fig. 3 is a perspective view of the locking device for the outer cone-shaped bearing and its supporting-nut. Fig. 4 is a perspective view of the outer cone-bearing detached. Fig. 5 is a plan view of the nut for 30 the outer end of the spindle. Fig. 6 is a side view of the outer cone-shaped bearing, the jam-nut, and the intervening double-locking washer on the outer end of the spindle, the rest of the spindle being broken away.

Like numerals of reference are used to 35 designate corresponding parts in the figures of the drawings.

In the drawings, 1 is a spindle on which revolves a shell 2, formed of a tubular piece of suitable material screw-threaded at its outer end. Ball-bearing cups 3 are driven 40 into the shell, one at each end, and a ball-bearing cone 4, having a screw-threaded interior, is screwed onto the outer screw-threaded end of the spindle. The other cone-shaped bearing 5 is formed as an integral part of the 45 spindle. Antifriction-balls 6 are placed in the raceways, formed, respectively, between the cones and the cups. The ball-bearing cone 4 is provided at its outer end with circumferential notches or serrations, and like 50 notches are made in the nut 7. As shown in Fig. 2, the spindle 1 is flattened at 8 by a

notch being cut in screw-threaded portions thereof, and a cone-lock and nut-lock device 9 (shown in Fig. 3) is set upon this flattened part of the spindle after the cone-shaped bearing 4 has been screwed onto the spindle 55 1 and all the parts have been assembled excepting the outer or jam nut 7. This cone-lock and nut-lock fastening 9 is preferably made of a single piece of steel, a part 10 being bent at a right angle to the vertical part 11, which latter is provided at its upper end with two teeth 12. On each side of the angle portion formed by the parts 10 and 11 may be parts 13, to be placed astride of the 60 screw-threaded end of the spindle, and thereby with the vertical part 11 serve in the nature of a washer when in use between the cone 4 and the jam-nut 7. At such time when all the parts are put together the teeth 12 are 65 turned down horizontally, one into a notch of the cone 4 and the other into a notch of the jam-nut 7, thereby locking both securely in their defined positions. This is found to be of prime importance, first securing the cone 70 4 from advancing on the screw-threaded portion of the spindle, and thereby jamming the balls in their inclosing cup-bearing, and also preventing said cone-bearing from receding on the screw-threaded spindle, and thereby 75 giving too much play to the antifriction-balls. Then as a secondary feature the jam-nut 7 is safely secured against accidental displacement when the pedal is in active use. This locking device not only serves for locking 80 both the cone-bearing and the jam-nut, but acts as a washer between the two, thus facilitating their conjoined action in providing a secure antifriction ball-bearing for a pedal. The teeth 12 may be readily relieved from 85 engaging in the notches 14 by straightening them up, whereupon the cone may be screwed on the spindle to take up wear of the ball-bearings when required or unscrewed to remove the pedal from the spindle. 90

I do not wish to limit my cone-locking device to any particular form of bicycle-spindle having ball-bearings and antifriction-balls, but to use the same in analogous forms of construction wherever found applicable. 95

The notch 8, while cut into the screw-threaded portion of the spindle, is placed inward 100

from its end to allow sufficient space thereon for receiving the jam-nut and allowing its internal screw-threads complete engagement with entire threads on the end of the spindle. 5 It thus provides a dust-proof construction and at the same time a complete screw-threaded holding engagement of said parts. This prevents dust passing (as it could to a greater or less extent) through a longitudinal groove 10 extending from the extreme end of the spindle inward beyond the washer to the cone-bearing and thence possibly into the ball-bearings. The jam-nut is positively locked when in use, as well as the cone-bearing part, 15 and the construction is in keeping with the requirements of being dust-proof, compact, strong, readily adjustable, and reliable as possible. The end of the spindle is perfectly round and not weakened or disfigured, and 20 the notch set back or inward therefrom need not be more than one thirty-second of an inch deep, thus weakening the spindle but in slight degree and providing a construction capable of minute adjustments, (without the 25 removal from the spindle of any of the parts,) as may often be found necessary in long-distance riding, racing, or in ordinary use.

Having thus fully described my invention,

what I claim, and desire to secure by Letters Patent, is—

30

1. A bicycle-spindle having a flattened notch portion 8 located inward from its screw-threaded end and a locking-washer having a part 10 fitting thereon, in combination with a screw-threaded cone-bearing 4 and the nut 7, 35 each provided with circumferential notches, the said washer having teeth 12 to engage in said notches, substantially as and for the purpose described.

2. A bicycle-spindle having a flattened 40 notch at its screw-threaded end and a locking-washer 9, having a part 10, extending at an angle therefrom and fitting in the notch, and parts 13 astride the spindle, in combination with the screw-threaded cone-bearings 4 45 and the nut 7, each provided with peripheral notches, the said washer having teeth 12 to engage in said notches, substantially as and for the purpose described.

In testimony whereof I affix my signature 50 in presence of two witnesses.

CASPER BICKEL.
